UNITED STATES PATENT OFFICE.

WALTER BOX, OF GEORGETOWN, TEXAS.

ENGINE.

1,203,574.

Specification of Letters Patent. Patented Nov. 7, 1916.

Application filed September 4, 1915. Serial No. 49,063.

To all whom it may concern:

Be it known that I, WALTER Box, a citizen of the United States, and a resident of Georgetown, in the county of Williamson 5 and State of Texas, have invented a certain new and useful Improvement in Engines, of which the following is a specification.

My invention relates to improvements in engines, and it consists in the combinations, 10 constructions, and arrangements herein described and claimed.

An object of my invention is to provide an engine of the internal combustion type with a rotary valve disposed in the cylinder 15 head, the movement of which affects the entrance of the explosive charge and permits the exhaust of the burnt gases.

A further object of my invention is to provide an engine having a rotary valve of 20 the type described in which there is no danger of leakage of the compressed gases due to the use of an expansion ring carried by the body of the valve.

A further object of my invention is to 25 provide a novel form of rotary valve for use with an internal combustion engine.

Other objects and advantages will appear 30 in the following specification, and the novel features of the invention will be particularly pointed out in the appended claim.

My invention is illustrated in the accompanying drawing forming part of this application, in which—

Figure 1 is a central sectional view 35 through one of the cylinders of the engine. Fig. 2 is a perspective view of the body portion of the valve. Fig. 3 is a perspective view of the expansion ring. Fig. 4 is a diagrammatic view showing a common valve 40 actuating shaft. Fig. 5 is a diagrammatic view showing the position of the valve during the "intake" stroke, Fig. 6 during the compression stroke, Fig. 7 during the explosive stroke, and Fig. 8 during the ex- 45 haust stroke.

In carrying out my invention, I make use 50 of a cylinder 1 having a crank case 2 in which is disposed a crank shaft 3, the latter being connected by means of a pitman 4 with the piston 5. In Fig. 1 I have shown a cylinder which is provided with a water jacket 6, but it will be understood that this invention 55 is equally applicable to air-cooled engines. At 7 I have shown a cylinder head which is held in position by means of bolts

7^a. The head 7 is provided with an inlet passage 8 and an exhaust passage 9 and with the usual spark plug 10. The head has a bore 11 arranged to receive a rotary valve like that shown at 12 in Fig. 2. This valve consists of a ring or wheel having a central portion 12^a connected to the outer body portion 12 by radially extending spokes or similar members 12^b. The valve stem 13 extends through the head 7 and is provided at its top with a gear 14 which meshes with a worm 15 on a shaft 16.

As will be seen from Fig. 2, there is an opening 17 in the ring or valve body 12. A slot or groove 18 which, it will be observed is wider than the opening 17, is provided in the outer periphery of the ring, but this slot terminates short of the opening 17, thereby providing shoulders 19. A spring expansion ring 20 is arranged to enter the groove or slot 18, this expansion ring being of such length as to permit the compression of the ring freely.

From the foregoing description of the various parts of the device, the operation 80 thereof will be readily understood.

Consider Fig. 4: In this figure there are four cylinders above which is disposed a drive shaft 16 which may be driven by the engine itself or from any suitable part of the crank shaft, not shown. The drive shaft 16 bears worms 15, each of the worms 15 engaging its respective gear 14 in the manner shown in Fig. 1. The movement of the shaft 16 causes the rotation of the valve stems 13 of the valves 12 of each of the cylinders.

Referring now to Fig. 5, the valve 12 is shown with its opening 17 in registration with the "intake" port 8 with the valve revolving in the direction shown by the arrow. In Fig. 6 the position of the valve 12 is shown during the compression stroke, in Fig. 7 during the explosive stroke, while in Fig. 8 the position of the valve is shown as changed to the extent that the opening 17 now registers with the outlet port 9 which communicates with the exhaust manifold. It will be seen that the valve is rotated once for every two revolutions of the main crank shaft.

The problem in devices of this kind has been to prevent the loss of pressure through the escapement of the gases past the rotary valve. In the present instance, however, I 110

have succeeded in preventing this from happening. The expansion ring always tends to hug the interior of the bore of the head closely so as to prevent the leakage of the gas. It will be observed that the expansion ring is protected from the pressure which is developed in the engine by the fact that it is virtually incased or housed by the valve body itself, so that even if high pressure is developed within the cylinder, it will not result in a corresponding increase of friction of the ring on the cylinder.

10 The use of the valve such as that described obviates the necessity of complex valve actuating mechanism, thus reducing the expense and the liability of the parts to get out of order.

15 In order to prevent the leakage of the gas past the shaft 13 in the cylinder head 7, I provide circumferential grooves 13^a in the shaft 13 in which the carbon will deposit, so as to make a self-cleaning packing. Ob-

viously asbestos or other suitable packing might be used.

1 claim:

20 In an engine, a cylinder, a head therefor having a cylindrical bore, said head being provided with an inlet port and an exhaust port, a hollow cylindrical body portion rotatably disposed within said bore, said body portion having an opening through one side arranged to register successively with said inlet and said exhaust ports, means for rotating said cylindrical body portion, said cylindrical body portion being provided on 35 its periphery with a circumferential groove in alignment with said opening, the ends of the groove terminating short of the opening on each side thereof, and a spring expansion ring disposed within the groove for 40 free expansion and contraction therein and arranged to cover and uncover said ports.

WALTER BOX.
